The ornamental design for paper product, as shown and described.

DESCRIPTION

FIG. 1 is a perspective view of a paper product showing our new design.

FIG. 2 is a top plan view of the paper product of FIG. 1.

FIG. 3 is a side plan view of the paper product of FIG. 1; and,

FIG. 4 is a front plan view of the paper product of FIG. 1. The paper product is shown broken away to indicate that the paper product has indeterminate length and width. The claimed design repeats uniformly throughout the length and width of the paper product.
